US00D375086S

United States Patent [19]
Kondo

[11] **Patent Number:** **Des. 375,086**[45] **Date of Patent:** ***** Oct. 29, 1996**[54] **ELECTRONIC COMPUTER**[75] Inventor: **Osamu Kondo**, Tokyo, Japan[73] Assignee: **Kabushiki Kaisha Toshiba**,
Kanagawa-ken, Japan

[*] Notice: The portion of the term of this patent subsequent to Jul. 19, 2008, has been disclaimed.

[**] Term: **14 Years**[21] Appl. No.: **37,162**[22] Filed: **Apr. 5, 1995**[30] **Foreign Application Priority Data**

[57] **CLAIM**

The ornamental design for an electronic computer, as shown and described.

DESCRIPTION

FIG. 1 is a top, front and right side perspective view of an electronic computer showing my new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a left side elevational view thereof;
 FIG. 7 is a right side elevational view thereof;
 FIG. 8 is a front elevational view thereof in a closed position;
 FIG. 9 is a right side elevational view thereof in the closed position;
 FIG. 10 is a top plan view thereof in the closed position; and,
 FIG. 11 is a top, front and right side perspective view thereof with the CD-ROM case being in an open position.
